UNITED STATES PATENT OFFICE.

ALBERT E. KALTSCHMIDT, OF DETROIT, MICHIGAN, ASSIGNOR OF THIRTY-FOUR ONE-HUNDREDTHS TO GEORGE W. WILLEBRANDS, OF DETROIT, MICHIGAN.

RAILROAD-CROSSING.

No. 909,189.

Specification of Letters Patent.

Patented Jan. 12, 1909.

Application filed November 22, 1907. Serial No. 403,346.

To all whom it may concern:

Be it known that I, ALBERT E. KALTSCHMIDT, a subject of the Emperor of Germany, residing at Detroit, in the county of Wayne and State of Michigan, have invented 5 certain new and useful Improvements in Railroad-Crossings, of which the following is a specification, reference being had therein to the accompanying drawings.

10 This invention relates to railway crossings and especially to means for temporarily filling the rails of either track to form a continuous tread.

The invention consists in the matters hereinafter set forth, and more particularly pointed out in the appended claims.

Referring to the drawings, Figure 1 is a plan view of a standard crossing equipped with a device embodying the invention. Fig. 2 is an enlarged view in detail of a filler block operating mechanism with casing cover removed, showing the block in position, when filling or closing a track. Fig. 3 is a view in vertical, central section of the mechanism. 25 Fig. 4 is a view in vertical central section taken at right angles to Fig. 3. Fig. 5 is a view in horizontal section on line $x-x$ of Fig. 3.

In the drawings, 1 and 2 indicate respectively the main line rails of intersecting tracks, with reinforcing rails 3, guard rails 4 and plates 5 all constructed and arranged in the usual manner. Connections 6 which are of the standard type used in signal and interlocking switch tower systems, and run from an operator's station or a switch stand to the crossing are coupled to a set of rack arms 7 which are each slidable in a casing or box 8 suitably secured as by flanges 9 bolted 30 to the track in an angle or corner of the crossing, whereby a set of fillers 10 on lifting arms 11 which are adapted to close the gaps in the rails of the cross-track 2 when in place, is swung in or out of position through mechanism in the casing operated by the rack arms. Similarly, other connections 12 operate a second set of fillers 13 for the track 1. The ratchet or rack arm 7 is reciprocable in a base plate 15 closing the casing, and meshes 45 with a pinion 16 fixed on the lower end of an upright cam cylinder 17 rotatably secured in the casing as by a stud 18.

A shaft 19 whose upper end above the casing cover 20 is connected to one end of the

lifting arm 11 is rotatably secured in the casing, its lower portion 21 being squared, flattened or splined to have non-rotative, sliding engagement with a part or mangled pinion 22 journaled in the casing and adapted to mesh with a partial or mangled gear 23 secured to or formed on the cam cylinder 17. The shaft is reciprocated by a cam yoke 24 rotatably interlocked therewith as by pins 25 riding in a peripheral groove 26, that has a cam roll 27 traveling in a peripheral cam path 65 28 on the cylinder, the casing preventing the turning of the yoke.

Pins 29 adapted to engage stops 30 in the casing limit the shaft to half a revolution. The shaft is held in its lowered position by a lock plunger 31 sliding in ways or a guide groove in the casing cover, that is moved in and out of an aperture 32 in the shaft by a cam roller 33 journaled on the plunger traveling in a cam path 34 on the upper end of the cylinder.

A check lock shaft 35 is rotatably secured in the casing horizontally over the upper end of the cam cylinder and a ward plate 36 is adapted to be snapped into a notch 37 in the cam cylinder by a properly disposed spring 38 unless the filler intercepts a rock arm 39 on the lock shaft when in its retracted lowered position.

In operation, a single complete movement 85 of the rack arm in either direction gives a single revolution to the cam cylinder. The lock plunger cam and lifting cam are so disposed relatively to each other that the plunger is withdrawn from the shaft and the latter is then raised by its cam yoke until the filler block is clear of the crossing rails. The cylinder gear and shaft pinion then intermesh and give the shaft a half turn, swinging the filler to the rear of the casing. The gear 90 and pinion then clear themselves, the shaft cam yoke roller lowers the shaft as it runs down the cylinder cam path, and the lock plunger is shot home. If the filler block has been damaged so as not to properly engage the check lock rock shaft, the check lock ward is snapped into the notch of the cam cylinder which is so placed that the cylinder is thus arrested before the operator's lever has reached its throw out position, thus locking the mechanism and compelling investigation before further use. Return of the rack to its initial position swings the filler

back to place. Either track may thus be cleared and a substantially continuous tread be presented by throwing the actuating lever.

The operating parts are incased and are 5 adapted to stand rough usage, and once adjusted are not liable to disarrangement and cannot be tampered with.

Obviously details of construction may be varied without departing from the spirit of 10 the invention and I do not care to limit myself to any particular form or arrangement of parts.

What I claim as my invention is:—

1. In a railway crossing, a vertical shaft, a 15 lifting arm extending radially therefrom, a filler block on the arm, means adapted to raise and lower the shaft and rotate it when elevated, and means to lock the shaft against movement when in its lower position, controlled by the operating means.

2. In a railway crossing, a casing, a vertical rotatable shaft longitudinally movable in the casing, a rotatable operating member in the casing adapted to raise and lower the 25 shaft and to give it a half turn when elevated, a longitudinally reciprocable member adapted to rotate the operating member, a radial lifting arm secured to the shaft, and a filler block secured on the filler arm.

3. In a railway crossing, a casing, a vertical rotatable shaft longitudinally movable in the casing, a cam yoke on the shaft, a cylinder journaled in the casing parallel to the shaft provided with a path engaging the yoke, 35 a mangled pinion non-rotatably and slidably secured on the shaft, a mangled gear on the cylinder adapted to intermittently engage the pinion, a rack pinion secured on the cylinder, a rack bar longitudinally movable in the casing in mesh with the rack pinion, a radial lifting arm secured to the shaft and a 40 filler block secured to the arm.

4. In a railway crossing, a casing, a mangled pinion journaled in the casing, a shaft 45 having non-rotative, sliding engagement with the pinion, a lifting arm extending from

the shaft, a filler block thereon, a plunger adapted to lock the shaft in its lower position, a cylinder journaled in the casing parallel to the shaft, a cam yoke on the shaft, a 50 cam on the cylinder engaged by the yoke and adapted to lift the shaft, a mangled gear on the cylinder adapted to engage and rotate the shaft pinion when the shaft is raised, a cam on the cylinder adapted to throw the 55 plunger into engagement with the shaft when the latter is lowered, a pinion secured to the cylinder, and a rack bar longitudinally movable in the casing in mesh with the pinion.

5. In a railway crossing, a casing, a mangled pinion journaled in the casing, a shaft having non-rotative, sliding engagement with the pinion, a lifting arm extending from the shaft, a filler block thereon, a plunger adapted to lock the shaft in its lower position, a cylinder journaled in the casing parallel to the shaft, a cam yoke on the shaft, a 60 cam on the cylinder engaged by the yoke and adapted to lift the shaft, a mangled gear on the cylinder adapted to engage and rotate the shaft pinion when the shaft is raised, a cam on the cylinder adapted to throw the 65 plunger into engagement with the shaft when the latter is lowered, a check lock shaft 70 journaled in the casing transversely to the cylinder, a ward plate thereon adapted to lock the cylinder when depressed, a spring adapted to depress the ward, a rock arm on the shaft exterior to the casing adapted to 75 be intercepted by the filler block when the latter is retracted normally, a pinion secured to the cylinder, and a rack bar longitudinally movable in the casing in mesh with the pinion.

In testimony whereof I affix my signature in presence of two witnesses.

ALBERT E. KALTSCHMIDT.
